EMBOSSED PLASTIC SHEET MATERIAL

Sharon De Leon, South Bend, Ind., assignor to United States Rubber Company, New York, N.Y., a corporation of New Jersey

Application March 26, 1959, Serial No. 55,182

Term of patent 7 years

(Cl. D87—3)

The figure is a plan view of a sheet of plastic material embossed with my new design.

A complete design unit is included within the broken-lines, and this unit is reproduced in regular succession throughout the width and length of the sheet material.

I claim:

The ornamental design for an embossed plastic sheet material, as shown.
